ABSTRACT

A welder's mask for use with a respirator includes an eye protecting window mounted on an integral face covering section which is provided with an enlarged depending bubble portion adapted to enable a welder to wear a respirator during welding operations while still assuring sufficient ventilation for the welder. The face covering portion of the welder's mask is provided with two side sections which extend rearwardly from the front of the mask for a distance sufficient to cover a welder's ears. The bubble portion of the mask is designed to be of sufficient volume such that when the mask is worn with a conventional respirator, at least two-thirds of exhaled air is expelled from the bubble volume thereby mixing with fresh air and, due to the chimney effect created by contact of warmer expelled air with fresh air, the latter is drawn upwardly and may be readily inhaled by the welder. By expelling the aforementioned fraction of exhaled air from the bubble volume, excessive, deleterious concentrations of carbon dioxide are inhibited from building up in the immediate vicinity of the respirator.

FIG. 1

FIG. 2

WELDER'S MASK FOR USE WITH RESPIRATOR

BACKGROUND OF THE INVENTION

This invention relates to a welder's mask and more particularly, to a welder's mask which may be worn with a conventional respirator device.

In order to provide adequate protection to a welder from heat, radiation, dust, fumes and sparks, etc. generated during welding operations, it has been common practice for welders to wear a protective mask or shield. Various forms of eye protecting windows with appropriate radiation shielding or filter devices are also standard elements of a welder's mask. One long-standing problem with welder's masks has been the difficulty in assuring adequate ventilation for the welder in order to avoid the deleterious effects caused by breathing of various contaminants, and yet assuring a sufficient supply of fresh air for breathing.

Attempts to solve the foregoing problem of satisfactorily ventilating a welder's mask have included the provision of a respirator worn together with the welder's mask. As conventional respirators are effective to inhibit the passage of contaminants to the welder during inhalation, the use of respirators has generally resulted in improved breathing by welders during typical welding operations. For example, a typical welder's mask incorporating a respirator device is illustrated in U.S. Pat. No. 3,232,290. In this apparatus, the respirator is merely mounted by means of a bracket onto the face covering portion of a welder's mask with no provision for assuring the removal of exhaled air being provided. It has also been suggested in the prior art to incorporate a fan or like device within a welder's mask to assure a desired flow of air behind the mask thereby assuring adequate ventilation for the welder and a welding mask or helmet incorporating such an electrical motor and fan arrangement is illustrated in U.S. Pat. No. 3,535,707. Although a degree of ventilation is provided by such apparatus, the welder's mask is rendered heavy, complex and costly by the incorporation of an electrical motor and fan arrangement for circulating air behind the mask.

Therefore, a clear need exists for a welder's mask which is both inexpensive and capable of mass production yet which is effective to protect the welder against heat, radiation and the like and most importantly, may be worn with a typical respirator and yet provide an adequate supply of fresh air for the welder.

OBJECTS OF THE INVENTION

Accordingly, it is an object of the present invention to provide a welder's mask for protecting a welder from excessive heat, radiation, dust, fumes, etc. during welding operations.

It is another object of the present invention to provide a welder's mask adapted to be worn together with a conventional respirator without significantly impeding breathing efforts of the welder.

It is a further object of the present invention to provide a welder's mask suitable for use with a respirator yet providing sufficient ventilation interiorally of the mask to avoid excessive concentrations of residual carbon dioxide accruing upon exhalation by the welder.

It is still a further object of the present invention to provide a welding mask suitable for use with a respirator wherein at least two-thirds of exhaled air is expelled from behind the respirator mask such that the forma-

tion of excessive concentrations of residual carbon dioxide in the immediate vicinity of the respirator are inhibited.

Other objects of the present invention will become apparent from the detailed description of an exemplary embodiment thereof which follows and the novel features of the present invention will be particularly pointed out in conjunction with the claims appended hereto.

SUMMARY

In accordance with the present invention, a welder's mask for use with a respirator includes an eye protecting window and an integral face covering section having side portions which extend rearwardly and a lower depending bubble portion of sufficient size to substantially encompass a respirator device. The bubble portion extends frontally from the wearer's chin for a distance of at least 7.5 cm. thereby defining a bubble volume of at least 500 ml. such that upon normal breathing by a welder, at least two-thirds of the exhaled air is expelled from the bubble volume. By configuring a welder's mask in accordance with the foregoing dimensions, adequate ventilation for a welder will be provided. Such ventilation accrues from the mixing of exhaled (CO₂ enriched) air with fresh air and, as exhaled air is normally warmer than fresh air, the aforementioned mixing will result in a "chimney effect" as mixed air will rise past the welder's head thereby inducing a flow of fresh air into the immediate vicinity of the respirator. Accordingly, by providing such ventilation of a welder's mask worn with a respirator, inhalation of excessive amounts of CO₂ is avoided and thus, improved welder breathing and ability to operate are achieved. In addition, by providing a lower, depending bubble portion in accordance with the present invention, proper positioning of the eye protecting window above the bubble portion is enabled. Thus, the bubble portion and the eye protecting window are effective to enable appropriate ventilation for, and viewing by the welder, respectively.

BRIEF DESCRIPTION OF THE DRAWING

The invention will be more clearly understood by reference to the following detailed description of an exemplary embodiment thereof in conjunction with the following drawings in which:

FIG. 1 is an isometric view of the front and side of an exemplary embodiment of a welder's mask provided in accordance with the present invention; and

FIG. 2 is a further isometric view of the rear portions and head harness of an exemplary embodiment of a welder's mask provided in accordance with the present invention.

DESCRIPTION OF PREFERRED EMBODIMENTS

Referring now to FIG. 1, there is illustrated an exemplary embodiment of a welder's mask 10 generally comprised of side portion 11, bubble portion 12 and eye protecting window 13. Welder's mask 10 is preferably comprised of a suitable plastic material or the like sufficient to withstand heat generated during a typical welding operation. Although other than plastic materials may be utilized, it is preferred to form mask 10 from a light a material as readily and economically possible. In addition, it will be understood that although mask 10 is herein described as intended for use by a welder,

mask 10 is suitable for protection against the aforementioned effects of heat, radiation, etc. regardless of the particular operation performed by the wearer. Side portions 11 of mask 10 are preferably substantially planar and extend from the frontal portion of mask 10 rearwardly for a distance sufficient to provide a covering of the ears of a welder. Bubble portion 12 is preferably configured in a substantially curvilinear fashion and is provided as a lower depending frontal and side portion of mask 10. The size of bubble 12 and the interior volume defined thereby is preferably sufficient to encompass and substantially surround a typical respirator (not shown) device worn by a welder during welding operations. In addition, the bubble portion is spaced sufficiently away from the welder's face and respirator to permit the expulsion of exhaled air from the bubble volume and the introduction of fresh air such that adequate ventilation for a welder may be effected.

The importance of providing a welder's mask 10 with a lower, depending bubble portion 12 will not be described. Typically, a respirator is provided with various filters and valves which although permitting the flow of relatively fresh or pure air therethrough also have a restrictive effect upon breathing by a welder or other individual. In addition, should the area immediately surrounding the respirator also be restricted such that the ready flow of fresh air to the respirator is reduced, significant impediments to breathing by a welder or other individual will be experienced. Therefore, a welder's mask must accommodate use of a respirator while simultaneously providing protection to the welder from heat, radiation or the like. In accordance with the present invention, it has been found that such dual protection can be achieved by configuring a lower, depending bubble portion 12 of sufficient size to permit free passage of air in and out of the bubble. However, although the size of the depending bubble portion 12 may be increased as aforesaid in order to enable such free passage of air, a further phenomenon which impedes breathing efforts must be considered. This phenomenon is the natural exchange of oxygen for carbon dioxide that occurs in the human lungs. Thus, in the exhalation process, there is an anatomical dead space beyond which the lungs cannot contract. This dead space is filled with residual carbon dioxide at the end of each exhalation phase which CO₂ is then mixed with the next inhalation of fresh air. Normally, the residual volume of CO₂ (in the human lungs) is relatively insignificant with respect to the tidal volume of air (volume of air per breath). Therefore, it is clear that in order to avoid significant impairment of breathing efforts, no additional CO₂ should be added, by inhalation, to the aforementioned residual carbon dioxide.

The use of a respirator by any individual has, in general, been found to increase residual CO₂ as the air contained within the respirator cavity at the completion of exhalation usually exhibits a higher than normal CO₂/O₂ ratio. This air is then re-inhaled ahead of fresh air drawn through filters of the respirator. Subsequent covering of the face and a respirator with a device such as a mask or the like that does not have sufficient ventilation will only generate a CO₂ enriched atmosphere in the vicinity of the respirator which in turn still further impedes normal breathing efforts. Thus, in accordance with the present invention, a welder's mask is provided with a lower depending bubble portion of sufficient volume to permit adequate ventilation, e.g. a sufficient

supply of fresh air, while also avoiding the creation of a CO₂ enriched atmosphere in the respirator vicinity. By configuring the welder's mask to be of sufficient size to enable adequate ventilation but yet of a size such that the major portion of CO₂ rich exhaled air is expelled from the bubble volume, the problems of supplying fresh air while avoiding CO₂ buildup of exhaled air are effectively solved by the welder's mask provided in accordance with the teachings of the present invention.

It has been found that an average individual wearing a respirator with inspiratory and expiratory resistances of 64 and 44 mm. H₂O, respectively, and performing work at a moderate rate of 622 kg-M/min. will have a respiration rate of 22.5 breaths/min. with a min. volume of 36.2 liters. The term "min. volume" is defined as the volume of air breathed per minute by an individual. Thus, a typical individual exhales 1.61 liters per breath. Preferably, bubble portion 12 of helmet 10 is configured to define a volume of at least 500 ml. and preferably of approximately 700 ml., which for a typical respirator occupying a volume of 200 ml. will provide an effective air volume of 500 ml. within bubble portion 12. It will be appreciated that as approximately 1.61 liters of air are expelled per breath, and only 500 ml. of such air may remain in the volume defined by bubble portion 12, at least two-thirds of the exhaled air (1.61-0.5/1.61) is forced from the volume defined by bubble 12 during expiration. In configuring the bubble portion 12 of mask 10 in the aforementioned volume, it is preferred to provide the frontal surface of bubble portion 12, i.e., that surface immediately below window 13, at a distance of at least 7.5 cm. from the normal location of a welder's chin thereby assuring sufficient clearance between a respirator worn by a welder and the frontal section of bubble portion 12.

As respirators are frequently designed with the expiration valve in the vicinity of the chin, it will be understood that the large opening of welder's mask 10 under the chin is effective to receive such exhaled air and allow the unrestricted flow thereof out of the rear portion of the mask. In addition, exhaled air is mixed and thus diluted with fresh air originally in the bubble and as such exhaled air is generally warmer than ambient air, the mixture will rise between the mask and wearer's face thereby causing a chimney effect which induces a draft of fresh air upwardly into bubble portion 12 of mask 10. In this manner, an adequate supply of fresh air into bubble portion 12 in the immediate vicinity of a respirator is obtained while the CO₂ rich exhaled air is caused to generally assume an upward flow away from the respirator device. Therefore, the provision of a bubble portion 12 with mask 10 as aforescribed achieves the dual objectives of providing a supply of fresh air to a respirator worn by a welder or the like as well as avoiding the accumulation of CO₂ rich exhaled air in the immediate vicinity of the respirator.

Referring again to FIG. 1 there is illustrated a portion of a head harness 14 and adjustment means 15 which upon manual operation thereof is effective to adjust the position of head harness 14 relative to the side portion 11 of welder's mask 10. Adjustment means 15 may comprise a conventional threadedly adjustable positioning device operated by means of a handle or knob as well known to those skilled in the art. Head harness 14 is more fully illustrated in FIG. 2, to which attention is now directed, and is comprised of a generally horizontal portion which may be adjusted in size by means

of a conventional adjusting device 17 and an upper band 18 which also may be adjusted in size by means of a belt buckle type adjustment 19. Adjustment means 16 which is preferably substantially identical to adjustment means 15 is provided on the other side portion 11 of welder's mask 10.

It will be realized by those skilled in the art that by appropriately adjusting means 15-17 and belt buckle type adjustment device 19, head harness 14 may be adjustably and securely fitted to the head of a welder with the mask portion 10 maintained out of contact from the welder's head thereby avoiding any problems such as skin irritation which may be caused from contact with welder's mask 10. Typically, head harness 14 and band 18 may be comprised of a flexible plastic material.

While the present invention has been particularly described in terms of specific embodiments thereof, it will be understood that numerous variations upon the invention are now enabled to those skilled in the art which variations are again within the instant teachings. Accordingly, the present invention is to be broadly construed and limited only by the scope and the spirit of the claims now appended hereto.

What is claimed is:

1. A welder's mask adapted to be worn with a respirator and comprising an eye-protecting window and an integral face covering section having side portions which extend rearwardly from a frontal portion and a lower, depending bubble portion of sufficient size to

encompass a welder's respirator, which bubble portion is spaced frontally from the welder's chin by at least 7.5 cm. thereby defining a bubble volume greater than 500 ml. such that upon breathing by a welder of 1.61 liters of air/min. at least two-thirds of the exhaled air is expelled from the bubble volume to thereby provide sufficient ventilation and to inhibit deleterious accretions of CO₂ in both the respirator and in the immediate vicinity of the welder's face.

10 2. A welder's mask as defined in claim 1 wherein the bubble volume is at least 700 ml. and the volume occupied by the respirator is approximately 200 ml.

15 3. A welder's mask as defined in claim 1 wherein said side portions extend rearwardly to a point approximately juxtaposed with the welder's ears.

4. A welder's mask as defined in claim 1 additionally comprising head harness means for supporting said face covering section in a position spaced away from the welder's head.

20 5. A welder's mask as defined in claim 4 wherein said head harness means is adjustable to enable fitting of said mask to different welders.

6. A welder's mask as defined in claim 1 wherein said eye-protecting window is located in the frontal portion 25 of said section above said bubble portion.

7. A welder's mask as defined in claim 1 wherein said bubble portion is configured with substantially curvilinear surfaces and said portions are substantially planar.
